(57) **CLAIM**

We claim the design for a lip for excavation bucket, as shown and described.

DESCRIPTION

FIG. 1 is an isometric view of a lip for excavation bucket showing our new design;

FIG. 2 is a front view thereof;

FIG. 3 is a back view thereof;

FIG. 4 is a top view thereof;

FIG. 5 is a bottom view thereof;

FIG. 6 is a right side view thereof; and,

FIG. 7 is a left side view thereof.
